UNITED STATES PATENT OFFICE.

FRANK A. LUNDQUIST, OF CHICAGO, ILLINOIS, ASSIGNOR, BY MESNE ASSIGNMENTS,
TO HENRY S. CONRAD, TRUSTEE.

AUTOMATIC TELEPHONE EXCHANGE.

Application filed August 16, 1917, Serial No. 186,448. Renewed April 19, 1923.

To all whom it may concern:

Be it known that I, FRANK A. LUNDQUIST, a citizen of the United States of America, and a resident of the city of Chicago, county of Cook, and State of Illinois, have invented certain new and useful Improvements in Automatic Telephone Exchanges, of which the following is a specification.

My invention relates to automatic telephone exchanges and has for its object improvements in such exchanges.

In telephone exchanges connections are made from place to place by trunk lines which are common for any one of a considerable number of subscribers, or a considerable number of switches representing subscribers. It is well known that the percentage of trunks required to carry the traffic decreases with the size of the group served by the trunks. Thus, when subscribers (or switches) are divided into groups of one hundred, the number of trunks required varies from twelve to fifteen per cent of the number of subscribers, and is usually estimated at fourteen per cent. When the groups are as large as one thousand, from four to six per cent is enough. It is here assumed as five per cent for convenience of description.

But to divide subscribers into large groups requires the use of switches of large size, that is, switches with many contact points upon them. The objection to such switches is not so much the size of the switch itself as the long rows of contacts used on such switches and the length of time required to move wipers over such rows by the step by step process. To understand that objection it is necessary to consider the calling device at the subscriber's station and the manner in which the subscriber operates this device. The impulses occurring in the exchange in response to operations of the calling device are of two kinds. First, those which correspond in number to some number or figure directly indicated by the calling device. Second, those used in hunting for an idle trunk and which are variable in number. Those of the second class are initiated at the calling device but continue automatically in the exchange until an idle trunk is found. For a variety of reasons it is desirable to make the calling device adhere to the decimal system of notation, and hence it is necessary, in large

switches, to add the extra contacts on those rows over which the wipers are automatically advanced. But subscribers habitually operate successive numbers with a degree of rapidity which makes from fifteen to twenty contacts in a row about the limit of what can be used in practice. If more are used, subscribers get indicated impulses piled upon automatic impulses with the result that there is a failure to make connections. One of the objects here is to provide ways for operating switches so, that, in their automatic movements, they can travel over long rows of contacts in the same limited time now required in traveling over short rows.

A typical organization on the plan here contemplated would contain the following apparatus for an exchange of ten thousand subscribers. There would be ten thousand line switches (one for each subscriber) arranged in ten groups of one thousand switches in each group. Each line switch would have contacts for fifty trunks, and all of the line switches of a group would be multiplied to fifty trunks leading to fifty selectors. It is practical to use such long rows of contacts on the line switches operating by the step by step principle because it is now the practice to cause the line switch to automatically start into operation by merely lifting the receiver from the hook. There would be ten groups of selectors with fifty switches in each group—each switch having five hundred contact terminals in ten rows of fifty each. A special movement is provided for automatically selecting an idle one of the fifty terminals in time not greater than that now employed in automatically selecting one of twelve or fifteen. There would also be ten groups of connectors with fifty switches in each group—each connector having one thousand terminals reached in three movements of the wipers. One of these movements is special for this type of connector. There would be no second selectors—a device now used in all automatic exchanges of ten thousand capacity.

In the accompanying drawings—

Fig. 1 is a condensed generalized diagram of part of an automatic telephone exchange arranged according to the plan herein indicated;

Fig. 2 is a diagram of the selector used;

Fig. 3 is a diagram of the connector; 110

Fig. 4 is a plan of a part of the selector, the wipers being advanced from normal position;

Fig. 5 is an elevation, partly in section, of 5 a portion of the selector; and

Figs. 6 and 7 are details of the bank contacts used in the selector.

The apparatus at the local stations is the same as that now in common use in automatic telephone exchanges and consequently 10 is not shown. The line switches may be any form of step by step apparatus which moves wipers over contacts, and are consequently only indicated by wipers and contacts. Such 15 wipers may be secured to the spindle of a ratchet wheel moved by a magnet in a manner similar to that shown for the side switch in the upper part of Fig. 2. The line relays are presumed to operate in the ordinary manner, and are only indicated. Other parts not 20 hereinafter fully described are assumed to be the same as those now in common use.

In Fig. 1 are shown three line switches provided with line wires 10 and 11 leading 25 to subscribers' stations. Bridged between 10 and 11 are the line relays 12 and 13, and a battery X provided with a ground connection. When a subscriber, as No. 1, removes his receiver he connects his lines 10 and 11 30 together to energize his relays 12 and 13 from battery X. This causes his wiper 14 to advance over its contact points until it finds the terminals of an idle trunk. When 35 this occurs the wiper is stopped on such trunk, and the relay 13 has its connection to battery and ground at some point as 15. The operation so far is of the ordinary and well known kind and needs no special description.

40 The trunk seized by a line switch is represented at the right of Fig. 2 by the lines 16 and 17. When this connection is made a current flows as follows: X-12-10-local station-11-14-16-18-19-ground-X.

45 This energizes relay 19 to attract its armature, whereupon a current flows as follows: battery Y-20-21-22-23-24-25-26-ground-Y. Also a branch from 23 to 27 and ground.

Relay 26 and release magnet 27 are copper 50 sheathed and consequently are slow magnets which do not release their armatures under rapid make and break of their circuits. In other words, 26 and 27 hold their armatures attracted during the sending of impulses to 55 be described later.

Relays 19 and 26 close a circuit from the battery Y for the magnet 28 to operate a ratchet wheel 29 as will be described later. Magnet 28 also closes a circuit as follows: 60 battery Z-magnet 30-31-32-33-ground-Z. Magnet 30 is also a slow magnet and controls the advance of the wipers 34, 24, 35 and 36 which constitute the side switch of the selector. This side switch is similar to the ordinary side switch, and the parts are so

arranged that the wipers 34, 24, 35 and 36 are simultaneously advanced when the magnet 30 is released.

When an impulse flowed thru the magnet 27 as before described, the armature 37 was 70 attracted to permit the driving pawl 38 and holding pawl 39 to engage the ratchet wheel 40 of the side switch. The driving pawl 38 is connected to the armature lever 41 operated by magnet 30.

Connected to the armature lever 37 is a link 42 which rests on the head of a pin 43, said pin being normally supported in an elevated position by a piston 44 in the cylinder 45. The space over the piston is connected thru pipe 46 with a vacuum maintained by a suction pump. In pipe 46 is a valve 47 normally held closed by a spring 48 on the stem of the valve. When the armature 37 is attracted the end of the link 42 is 80 moved clear of the end of the valve stem, and when the piston 44 descends in the cylinder 45, the end of link 42 drops to a level with the end of the stem of valve 47. When the armature 37 is later released, the 85 spring on said armature overcomes the spring on the valve stem to open the valve 47. When this occurs the vacuum over the piston 44 acts to raise it to its upper or normal position. In thus rising the piston 44 90 pushes up pin 43 to move link 42 clear of the end of the valve stem.

Secured to the piston 44 is a flat rod 49 having in it a hole 50, and a series of other holes 51. (See Fig. 5.) Supported adjacent to the rod 49 is a hook 52 which normally engages the hole 50 and supports rod and piston in the position shown in the drawings. The hook 52 has an armature arranged to be acted upon by magnet 53 105 to release said hook and permit piston and rod to fall by gravity. The piston 44 is somewhat loose in the cylinder 45, and there is also a certain amount of air leak around pin 43. This leak permits the piston to drop with a moderate degree of velocity when released, but is not enough to prevent the rise of the piston when the vacuum is applied by opening valve 47.

Pivoted at a convenient point is an arm 115 54 which is normally supported in the position shown in Fig. 2, but is provided with an escapement 55 operated by a magnet 56. Each time an impulse flows thru magnet 56 it permits the arm 54 to fall by gravity 120 one step. The outer or free end of arm 54 is adjacent to the rod 49 and has pivoted thereon a catch lever 57 arranged to engage one or another of the holes 51 in rod 49. In normal position a projection on 125 armature 37 engages a tail piece on catch lever 57 to hold said catch lever away from rod 49. But when armature 37 is attracted by magnet 27, the projection moves away from the tail piece and permits catch 57 to 130

engage any hole 51 which may at the time be opposite the catch.

The upper end of the armature which carries hook 52 extends around the rod 49 and has a projection 58 which lies between said rod and a part of the body of the catch lever 57. Whenever the magnet 53 operates to move its armature, the projection 58 pushes catch lever 57 away from engagement with rod 49. Upon the actuation of magnet 53, the hook 52 is released and the rod 49 drops. As there is only one hole 50 for the hook 52, breaking the circuit at a later time thru 53 lets the point 15 of hook 52 rub against the side of rod 49. In this position the projection 58 is not so far out as to prevent the catch 57 from engaging one of the holes 51. But after such engagement of catch 57, an actuation of 20 magnet 53 will cause projection 58 to release catch 57.

The bank contacts are arranged in ten vertical rows as shown in plan in Fig. 4. The terminals for each line are represented 25 by three contacts, the center one of which is the private contact and is longer than its two associates as shown in Figs. 4 and 7. The vertical rows contain fifty, more or less, such terminals of three contacts each. 30 The lower end of the rod 49 enters the open end of a slotted tube 59 upon the upper end of which is the ratchet wheel 29. The lower end of the rod 49 terminates in a ball 60 which is pivotally connected to a 35 block 61 arranged to slide vertically in the tube 59. On the block 61, and projecting laterally thru the slot in the side of the tube 59, are two contact carrying arms 62 and 63. The upper arm 62 carries the ordinary three wipers used in any ordinary 40 trunk selecting switch. One of these three wipers is the private wiper, and the other two are the wipers which close the two sides of a talking circuit. The lower arm carries 45 an additional private wiper the purpose of which will be further explained hereinafter.

On the lower end of the tube 59 is a spring 64 which normally turns said tube 50 so as to hold the arms 62 and 63 at the position shown in dotted lines in Fig. 4. On the armature 37 is an arm connected to a rod 65 which normally rests upon a holding pawl 66 and holds said pawl from engagement with ratchet wheel 29. When 55 however, armature 37 is attracted by magnet 27, the rod 65 is raised and the holding pawl 66 is free to engage ratchet wheel 29. If, after this occurs, magnet 28 should operate upon its armature 67, the driving pawl 68 will move the ratchet wheel 29 to advance arms 62 and 63, and thus bring 60 their wipers over any desired vertical row of contacts in the bank 69. In this turning, the tube 59 revolves about but does not

turn the rod 49. To make a fairly accurate guide for the arms 62 and 63, the sides of the slot in tube 59 are preferably provided with guiding flanges 169.

The magnet 27 is a slow magnet and 70 holds its armature 37 attracted until the calling subscriber returns his receiver to its hook. It will be seen by the foregoing description that the attraction of armature 37 accomplishes several things. First, it 75 releases the pawls for the ratchet wheel 40 which controls the side switch. Second, it releases the holding pawl 66 for the ratchet wheel 29. Third, it releases the catch lever 57 so that it may engage an opening in the 80 rod 49. And fourth, it moves the link 42 to the right to a position in which it can operate upon and open valve 47.

In making a call the subscriber removes his receiver which automatically closes a 85 contact at the local station and brings about those operations, previously described, which result in an impulse from battery X reaching line 16 (Fig. 2) and the consequent operations of magnets 19, 26 and 27. 90 Magnets 28 and 30 are not operated by this first impulse reaching line 16 because relay 19, in attracting its armature, breaks the circuit for magnet 28, and the circuit for magnet 30 is closed only by magnet 28. 95

The next thing the subscriber does after removing his receiver is to operate his calling device by pulling on its dial the first digit found in the number which represents the subscriber to be called. It will be assumed that this is represented by the numeral "5". In doing this the subscriber sends rapidly five impulses from battery X to relay 19 over the path previously described. As the relay 19 is energized at the 100 beginning of this operation, the first impulse breaks and then remakes the circuit for 19, and the last one of the five leaves the circuit closed with the relay energized.

Because 26 and 27 are "slow", they hold 110 their armatures attracted during the operation of relay 19. When the armature 20 of relay 19 falls back against its back contact it closes the circuit for magnet 28, and when 20 is again attracted the circuit is broken for 115 28. In other words, relay 19 and magnet 28 operate alternately. Each operation of magnet 28 advances the ratchet wheel 29 so as to move the arms 62 and 63 over the vertical rows of contacts in bank 69. As we assumed 120 "5" for the first number, the completion of these impulses would leave arms 62 and 63 in the position shown in full lines in Fig. 4.

As magnet 28 closes the circuit for the slow magnet 30, this last named magnet attracts its armature 41 and holds it until the circuit is finally broken thru magnet 28. When this occurs the retracting spring on armature 41 moves that armature to advance the side switch wipers 34, 24, 35 and 36 one 130

step from this position shown to the next contact points in their paths. This action closes a circuit as follows:—battery Y-20-21-22-23-24-70-71-magnet 53-72-wiper 73-5 contact 74 with which wiper 73 is normally in engagement-ground-Y.

The operation of magnet 53 releases the hook 52 and at the same time causes projection 58 to push catch on lever 57 away from 10 the rod so that said catch will not fall into any hole 51 in said rod. The release of hook 52 permits rod 49 and connected parts to fall by gravity and the brushes on arms 62 and 15 63 to travel along the contacts in the selected fifth vertical row of bank 69.

As these parts fall, the wiper or brush 73 moves from contact to contact. If the next 20 private contact in the vertical row has a ground connection the circuit thru magnet 53 will be maintained and the catch on lever 25 57 will be held away from the rod 49. But when the wiper 73 comes to a private contact which has on it no ground connection, then the circuit will be broken thru magnet 53 and the catch on lever 57 will be permitted to fall into a hole 51 and stop the further descent of 30 the rod 49 and connected wipers.

The magnet 53 has a second armature 75 which closes a circuit at 77-78 for magnet 30 30 at the time when magnet 53 is energized as just described. This circuit is: Z-30-31-76-77-78-ground-Z. This attracts armature 41 as before so that when the circuit is again 35 broken thru magnet 30 as a result of breaking it thru magnet 53, the retracting spring moves armature 41 to again advance the side switch to bring wiper 34 on contact 83.

In this last position a circuit is completed 40 as follows:—battery W-79-80-81-56-82-83-34-85-private wiper 86^a grounded contact 45 previously engaged and passed by the wiper 73, and thence back to battery W.

The actuation of magnet 56 operates the 50 actuation of magnet 56 operates the escapement 55 to permit the arm 54 to descend. As the armature of the magnet 56 makes and breaks its own circuit at 80-81, this descent is step by step. As the catch on lever 57 is at this time in a hole 51 in rod 49, this descent lowers the wipers on said rod 55 50 step by step from one contact to another. As long as the wiper 86 finds a grounded contact to engage with, the magnet 56 will continue its operation, but as soon as wiper 86 comes to a contact having no ground (which 60 will be the one previously engaged by wiper 73), the circuit for magnet 56 will be permanently broken and the escapement 55 will cease to operate.

The distance between the wipers 73 and 65 86 will usually be about two or three steps of the escapement 55. The object in using these two wipers and associated parts is to divide the long movement, over long rows of contacts, into two parts. The first of these is a rapid 70 and continuous movement terminating in an

approximate selection of the first idle trunk. The second part consists in one, two, three or more steps, and terminates in an accurate selection of the first idle trunk. As long as the approximate selection falls short of having the talking wipers connect with the first idle trunk, it is immaterial to what extent 70 it falls short, provided it is within reasonable limits. A selector switch may at one time fall short one step; at another time the same switch may fall short two steps; and at still other times it may fall short three steps. Whatever the shortage may be, the escapement 55 will make it up by the proper number of steps. As a consequence of this arrangement, no careful adjustment of parts is necessary in terminating the first part of the automatic trunk selecting movement.

When the magnet 56 operates as previously described, it closes contacts 87-88, 85 thus completing a circuit as follows: battery Z-30-31-76-87-88-ground-Z. This again attracts armature 41, and when the circuit is finally broken thru magnet 56, the wipers of the side switch are advanced to their final 90 position. In this position the wiper 34 places ground connection on the private wiper 86, and consequently on all multiple connections of the particular contact with which that wiper is at the time engaged. In 95 this final position the wipers 35 and 36 connect to lines 17 and 16 from the line switch, and by means of wires 89 and 90 extend the connections to wipers 91 and 92 in engagement with trunk terminals in bank 69. The 100 terminals engaged are represented at the right of Fig. 3 by wires 93 and 94.

In the position just described relays 95 and 96 of the connector are actuated from battery X¹ over a circuit which includes 105 ground and the connections back to the local station. Relay 95 is a slow relay which will hold its armature attracted while the calling device is being actuated manually to send rapid impulses thru magnet 96.

Upon relays 95 and 96 being actuated by reason of the side switch wipers 35 and 36 connecting back thru the local station, these magnets attracted their armatures. The circuit resulting is as follows:—battery 115 X¹-97-98-99-100 and 146-ground-X¹. Magnet 100 is a slow magnet which will hold its armature attracted during rapid movements of armature 97. The attraction of armature 101 by magnet 100 releases holding pawls 120 102, 103, 104 and driving pawl 105 and lets these pawls engage their respective ratchets. Magnet 146 is also a slow magnet which holds its armature and controls a link 147 which corresponds to link 42. These parts 125 control vacuum over the piston 135 in exactly the same way that the previously described parts control vacuum over the piston 44.

The attraction of the armature 107 of 130

relay 95 does not affect the operation of the switch in the first instance because the connection from battery X^1 is broken by the attraction of armature 97 of relay 96. But 5 upon operating the calling device at the local station the circuit for 96 is broken and remade some definite number of times—from one to ten times. Upon the first break a circuit is completed as follows:—X ^{1} —97—106—10 107—108—magnet 109—110—side switch wiper 111—contact strip 112—113—ground—X ^{1} . Also a branch extends from 108 as follows:—114—side switch wiper 115—116—magnet 117—ground—X ^{1} . 15 Magnet 109 is a slow magnet which holds its armature during the operations of relay 96 under impulses controlled from the calling device. Magnet 117, however, responds to these impulses and attracts its armature 20 119 which carries pawl 120. This pawl operates on ratchet wheel 121 to turn tube 122. In this tube is a block 123 having an arm 124 projecting thru a slot in the tube and carrying wipers 125 and 126 adapted to engage 25 selected contacts in the bank 127. These parts correspond to the similar parts in the selector switch previously described, and the number of impulses sent by the calling device determine to what position the 30 wipers shall be moved over the bank 127. The contacts in this bank are the line terminals for the subscribers in the exchange, and are arranged in ten vertical rows. In a ten thousand exchange, each vertical row 35 would contain terminals for one hundred stations.

Upon the completion of a series of impulses due to operating the calling device at the local station, the circuit is left completed 40 thru relay 96. The consequent attraction of armature 97 breaks the circuit for magnet 109, whereupon its armature 118 falls back to advance the side switch wipers one step. Wiper 111 rests upon a continuous strip 112 so that the advance of this wiper changes nothing. Wiper 115, however, is shifted from connection to magnet 117 to connection to magnet 128 so that the 45 next series of impulses sent by the calling device will flow thru the last named magnet.

Armature 129 of magnet 128 bears against a rod 130 which carries a pawl 131 arranged to engage ratchet teeth on a slide 132. On 50 the other end of slide 132 is a pawl 133 which engages a notch in flat rod 134 connected to piston 135 in cylinder 136. These parts are similar to parts previously described for the selector switch.

In the rod 134 is a series of five pins 137 and a second series of five pins 138. These pins are offset as shown and not in vertical arrangement over each other. The amount 55 of offset from one pin to the next equals the spacing of the teeth on slide 132. Carried

on said slide are pins 139 and 140 which are arranged to cooperate with pins 137 and 138.

When magnet 128 moves the slide 132 one step to the left it moves pin 139 under the lowest one of the pins 137 and at the same time releases pawl 133 from rod 134. This permits rod 134 and connected parts to drop to a position which will bring the wipers 125 and 126 in engagement with the uppermost terminals in that particular row in 70 bank 127 which was previously selected by the operation of magnet 117. When magnet 128 moves slide 132 the second step, pin 139 moves from its position under the lowest pin 137 to a position under the next pin 80 137 and permits rod 134 and connected parts to again drop. The amount of this second drop is equal to the space occupied by ten sets of terminals in bank 127 and leaves the wipers 125 and 126 in engagement with the 85 eleventh set of terminals in the selected row. The third operation of magnet 128 permits the parts to again drop and come to rest with the wipers 125 and 126 on the twenty-first set of terminals. And so on. After 90 the fifth drop, pin 140 comes under the lowest pin 138, and then successively under the other pins.

The number of impulses sent by the calling device thru magnet 128 will depend 95 upon what group of ten terminals is wanted in the previously selected vertical row. When this group is reached the impulses stop, and the side switch wiper 115 is advanced in the manner previously described 100 from connection with magnet 128 to connection with magnet 141. This last magnet controls an escapement 142 which permits slide 143 to move downward step by step as magnet 141 is operated. Slide 143 is guided 105 by slots 144 operating on pins 145 secured in a convenient part of the frame work of the apparatus. The spacing of the ratchet teeth in escapement 142 corresponds to the spacing of the terminals in bank 127 so that 110 each operation of the magnet 141 lowers the wipers 125 and 126 from one set of terminals to the next. This is made possible by carrying the slide 132 on slide 143 so that lowering slide 143 lowers the rod 134 and 115 its connected parts.

The number of impulses sent by the calling device thru magnet 141 depends upon the particular unit desired in the group of ten previously selected by magnet 128. 120 When the impulses thru magnet 141 stop, the side switch wipers 111 and 115 are advanced as before, but now rest upon blank contacts. Wire 148 connects wire 93 to wiper 125, and wire 149 connects wire 94 to 125 wiper 126. Hence it will be evident that upon completion of the operations of magnet 141, the calling station will be connected by wires 10 and 11, wires 16 and 17, wires 93 and 94, wires 148 and 149, and wipers 130

125 and 126 with the terminals of a called station as those terminals are found in bank 127.

Associated with wipers 125 and 126 there will be, of course, a private wiper and suitable connections for preventing interference with a busy line. Such private wiper and connections are well known things and form no part of the present invention. As a consequence they are not described. The manner of signalling the called station is also a well known thing and not described.

When conversation is finished, the calling subscriber hangs up his receiver. The effect of this is to break the connection between lines 10 and 11 in the ordinary manner. The effect of such break is to cause the line switch to return to normal position in a manner common in the primary switches in ordinary automatic telephone exchanges. The details of the operations of the line switch for bringing about such return form no part of the present invention and are not described.

25 The breaking of the connection at the calling station also breaks the circuit for relay 19 and permits its armature 20 to fall back and thus break the circuit for the magnet 27. As a consequence of this last break, the 30 armature 37 falls back and the pawls 38 and 39 are lifted from engagement with the ratchet wheel 40. Thereupon the side switch of the selector returns to normal position in the ordinary manner.

35 The retraction of armature 37 causes the link 42 to engage the valve stem and open valve 47. This permits the air over piston 44 to be drawn out so as to cause the piston and connected parts to rise to normal position. At its upper position the piston strikes pin 43 which pushes link 42 from engagement with the stem of valve 47. At the same time the hook 52 falls into the hole 50 and thus prevents the piston 44 from falling 45 when the valve 47 closes. The same retraction of the armature 37 causes rod 65 to lift pawl 66 from ratchet wheel 29 so that spring 64 may rotate the wiper arms 62 and 63 and associated parts back to normal position.

50 The retraction of armature 37 does not immediately release the catch on lever 57 because the fall of rod 49 and arm 54 had carried the tail piece 150 away from the arm 151 on armature 37. The catch on lever 57 is shown undercut at 152, and the lower edge of hole 51 in which this catch is engaged this undercut and lifts arm 54 when the piston 44 rises. In rising the piston 44 passes a little above its normal position and is stopped by engaging the boss in which pin 43 is located. In the extreme upper position of the piston 44 the arm 54 is raised high enough to permit the escapement 55 to catch in the lowest ratchet tooth as shown in Fig. 2. At this time the undercut 152 is still in

engagement with the edge of the hole 51 in rod 49. The tail piece 150 engages the arm 151 and moves the armature 37 as if it were attracted by its magnet 27. However, the other parts are in such a position that this movement of armature 37 accomplishes nothing beyond putting a tension on the catch lever 57 at the undercut 152. When the valve 47 closes, the piston settles down a short distance until stopped by the hook 52. This settling of the piston 44 and rod 49 releases the engagement with the undercut 152 and permits the retracting spring on armature 37 to move the lever 57 to the position shown.

80 The breaking of the circuit at the calling station breaks it also for relay 96 of the connector, which in turn breaks the circuit for magnets 100 and 146. The consequent retraction of armature 101 lifts pawls 102, 103 and 105. This permits the side switch, and ratchet 121 and associated parts, to return to normal position as in the case of the selector.

85 The operation of magnet 146 moves the link 147 and results in the rise of piston 135 and connected parts exactly as the movement of link 42 resulted in the rise of piston 44. On that part of the rod 134 which extends below the horizontal extension 153 of the slide 143 is a collar 154 which engages the under part of 153 and raises the slide to the normal position shown in Fig. 3. Just as these parts are arriving at their uppermost position the tail of the pawl 104 engages the adjacent part of armature 101 so that pawl 104 is released and spring 155 retracts the slide 132 to bring pawl 133 again into position to support rod 134. These various movements leave the parts all in their original position from which they can be moved again for some other selection.

90 Fig. 3, which is principally diagrammatic, shows the pins 137, 138, 139 and 140 as if they were all on one side of the rod 134. In practice it is preferable to have pins 137 and 139 on one side, and pins 138 and 140 on the other side, with the rod 134 passing thru an opening in the slide 132. The reason for this is simply to prevent interference of parts in the restoring movement.

95 Fig. 1 shows, in much condensed form, a part of an exchange for ten thousand subscribers arranged in accordance with the plan outlined. No. 1, No. 2 and No. 3 represent connections to three line switches in a group of one thousand such switches. The wipers of these switches (represented by one wiper 14 for each switch) are arranged to sweep over fifty sets of terminals multiplied to the bank wires K. From these bank wires or trunks, taps 16 and 17 lead to fifty selector switches, three of which are represented at A, B and C. The next group of one thousand line switches would lead in the 100

same way to another bank of fifty trunks, and from these similar taps would lead to fifty other selectors constituting the second group.

- 5 By the operation previously described the side switch wipers 35 and 36 are moved so as to extend the connections 16 and 17 to the selector wipers, one of which is represented at 91 in Fig. 1. Each selector has ten vertical rows of trunk terminals with fifty trunk terminals in each vertical row. Fig. 1 represents at 69 one such vertical row for each of the switches A, B and C. All of the trunk terminals of the first vertical row of all of 10 the selectors are multiplied together and lead to the fifty connectors in the first group, three of which are shown at L, M and N. The terminals of the second vertical row are similarly multiplied together and lead to the 15 fifty connectors of the second group. And so on.

When a selector switch is operated its wipers extend the connections to lines 93 and 95 in some connector, (L, M or N), in a 20 previously selected group.

Each connector has terminals for one thousand subscribers' lines, and the terminals in fifty connectors are multiplied together so that any one of the fifty connectors may 25 complete connections to any one of the one thousand subscribers in the group. These terminals are placed in ten vertical rows with one hundred terminals in each row. A part of one of such rows is shown at 127 in Fig. 30 35 1 for each of the connectors L, M and N. The connections back from these terminals to the lines 10 and 11 of the local stations may be readily traced on Fig. 1 and need no special description.

40 What I claim is:

1. The combination with a long vertical row of terminals, and wipers for engaging such terminals, of pneumatic devices for moving said wipers upward and releasing devices for permitting them to move downward by gravity, magnetic means for controlling the pneumatic and releasing devices, and magnetically operated intercepting devices so arranged as to cause said 45 wipers to move by successive long and short steps from one end of the row to a particular terminal therein.

2. The combination with a long row of contact terminals representing trunks, of a 50 wiper and carriage therefor, means for causing said carriage to advance rapidly so that said wiper will move from terminal to terminal in said row, means controlled by engagement of said wiper with the terminal of an idle trunk for arresting the movement of the carriage, a second wiper on said carriage, means for causing said carriage to move slowly to carry said second wiper to engagement with the terminal previously engaged 55 by the first wiper, and automatic means for

again arresting said carriage when the second wiper engages said terminal.

3. The combination with trunk terminals, of a carriage having two wipers thereon for engaging said terminals, means for starting 70 said carriage at high speed, means controlled by engagement of one of said wipers with the terminals of an idle trunk for changing the carriage movement from high speed to slow speed, and means controlled by engagement of the other wiper with the same terminal for arresting the carriage movement. 75

4. Wipers secured to a rod arranged to be moved when released, pins in offset arrangement extending from the side of said rod, 80 an intercepting device arranged to be engaged by said pins, means for moving the intercepting device laterally step by step so as to permit said rod to move axially step by step, and separate means for moving said 85 intercepting device in a direction parallel with the axis of the rod so as to give said rod other step by step movements.

5. The combination with trunk terminals, a carriage having two wipers for engaging 90 said terminals, and means for giving said carriage a rapid movement, of means controlled thru one of said wipers for reducing the speed of the carriage movement, and means controlled thru the other wiper for 95 stopping said movement.

6. The combination with trunk terminals, a carriage and means for giving it a movement, and two wipers on said carriage for controlling such movement, one wiper being 100 in advance of the other and normally active and the rear wiper being normally inactive, of means by which upon the active wiper engaging the terminal of an idle trunk the said active wiper will become inactive and the 105 normally inactive wiper will become active and at rest upon the terminal first engaged by the forward wiper.

7. The combination with trunk terminals and a movable switch having two trunk 110 hunting wipers thereon for controlling the switch, one wiper being in advance of the other, of means by which upon the leading wiper engaging the terminals of an idle trunk such wiper will become inactive and 115 the control will pass to the following wiper through the terminal first engaged by the leading wiper.

8. The combination with trunk terminals, and a trunk hunting switch, of means by 120 which the terminal of a found trunk cooperates initially with an advanced point on the switch and later with another point on the switch to the rear of the advanced point.

9. The combination with a series of long rows of trunk terminals, and wipers for engaging said terminals, of a step by step device for moving said wipers from normal position to a position adjacent to a desired 130

- row of terminals, a continuous movement device for advancing said wipers at high speed along the selected row of terminals, means for automatically stopping said continuous movement device so as to arrest the wipers adjacent to but before reaching the terminals of an idle trunk, and a second step by step device for moving the wipers from their arrested position to the idle trunk.
10. The combination with trunk terminals, a carriage having two wipers for engaging said terminals, and means for giving said carriage a rapid movement, of means controlled thru said wipers in succession for stopping said carriage at a position corresponding to an idle trunk.
11. In a telephone system, trunk terminals divided into rows, said rows divided into groups, wipers for engaging said terminals, means for rotating said wipers step by step into alignment with a desired one of said rows, a rod, said wipers secured to said rod but rotatable independent thereof, said rod arranged to be moved by gravity when released, arms on said rod staggered diagonally and spaced from each other a distance equal to the length of one of said groups, an intercepting device arranged to be engaged by said arms, means for moving the intercepting device step by step in one direction so as to permit said rod to move step by step to select a desired group in the selected row, and additional means for moving the intercepting device step by step in a different direction to select a desired terminal in the selected group.
12. In a telephone system, trunk terminals divided into rows, said rows divided into groups, wipers for engaging said terminals, means for rotating said wipers into alignment with a desired one of said rows, a rod, said wipers secured thereto but rotatable independent thereof, said rod arranged to be moved by gravity when released, arms on said rod staggered diagonally and spaced from each other the distance equal to the length of one of said groups, an intercepting device arranged to be engaged by said arms, means for moving the intercepting device in one direction so as to permit said rod to move said wipers to select a desired group in the selected row, and separate means for moving the intercepting device in a different direction to move said wipers to select a desired terminal in the group.
13. In a telephone system, trunk terminals divided into rows, said rows divided into groups, wipers for engaging said terminals, means for rotating said wipers into alignment with a desired one of said rows, a rod, said wipers secured to said rod but rotatable independent thereof, an intercepting device, means for moving the intercepting device so as to permit said rod to make a corresponding number of movements to move said wipers opposite a desired group in the selected row, and additional means for again operating said intercepting device to move said wipers in engagement with a desired terminal in the selected group.
14. In a telephone system, trunk terminals divided into rows, said rows divided into groups, wipers for engaging said terminals, means for rotating said wipers into alignment with a desired one of said rows, a rod, said wipers secured to said rod but rotatable independent thereof, an intercepting device, means for moving the intercepting device a number of steps so as to permit said rod to move said wipers a corresponding number of steps opposite a desired group in the selected row, and additional means for again operating said intercepting device in a different direction to move said wipers step by step into engagement with a desired terminal in the selected group.
15. The combination with trunk terminals, and a trunk hunting switch having two trunk hunting wipers one of which is in advance of the other, of means by which the terminal of an idle trunk co-operates initially with said advanced wiper and later with said other wiper to allow said switch to come to rest on said idle trunk.
16. The combination with trunk terminals, a carriage having two wipers for engagement with said terminals, one of said wipers being in advance of the other wiper, and means for giving said carriage a rapid movement, of means by which said advanced wiper controls the extent of travel of said carriage in its rapid movement, of means for switching the control of the movement of the carriage from said advanced wiper to the other wiper, and of means controlled through said other wiper for moving said carriage step by step and for stopping said carriage at a position corresponding to an idle trunk.
17. The combination with a long row of contact terminals representing trunks, of a wiper and carriage therefor, means for causing said carriage to advance rapidly so that said wiper will move from terminal to terminal in said row, means controlled by engagement of said wiper with the terminal of an idle trunk for arresting the movement of the carriage, a second wiper on said carriage, means under control of said second wiper for moving said carriage step by step until said second wiper comes into engagement with said terminal previously engaged by said first wiper, and automatic means for again arresting said carriage when said second wiper engages said terminal.
18. In a telephone system, trunk terminals, a carriage having two wipers for engaging said terminals, means for rotating said carriage to place said wipers in aline-

ment with a desired row of said terminals, a catch for holding said carriage in elevated position, means for operating said catch to allow a rapid movement of said carriage, 5 means controlled through one of said wipers for reducing the speed of the carriage movement when said one wiper engages an idle trunk terminal, and means controlled through the other of said wipers for continuing said movement by a step by step movement until said other wiper engages with said idle trunk terminal.

19. In an automatic telephone exchange, the combination with trunk terminals and 15 wipers designed to make electrical connection with said terminals, of means for moving said wipers to automatically select an idle trunk, such movement being divided into two parts, the first part under control 20 of one of said wipers and being a rapid con-

tinuous movement terminating in the approximate selection of an idle trunk, and the second part under control of a second of said wipers being a slower step by step movement in the same direction which terminates in an accurate selection of said idle trunk. 25

20. The combination with line terminals, and wipers for engaging said terminals, two of said wipers being trunk hunting wipers, of means for permitting said wipers to fall 30 by gravity toward a desired terminal, means under control of one of said trunk hunting wipers for stopping such fall when said wipers are within a short distance of the desired terminal, and a device under control of the second trunk hunting wiper for moving said wipers step by step in the same direction from stopped position to the desired terminal. 35

FRANK A. LUNDQUIST.
